UNITED STATES PATENT OFFICE

EDWIN A. GUINZBURG, OF NEW YORK, N. Y.

DESIGN FOR A BATHING-STOCKING.

SPECIFICATION forming part of Design No. 27,582, dated August 31, 1897.

Application filed December 19, 1896. Serial No. 616,342. Term of patent 7 years.

To all whom it may concern:

Be it known that I, EDWIN A. GUINZBURG, a citizen of the United States, residing at New York city, in the county and State of New York, have invented and produced a new and original Design for Bathing-Stockings, of which the following is a specification.

The accompanying drawing represents the appearance of my new bathing-stockings.

10 The leading characteristic of this design is the appearance of a slipper upon the foot portion of the stocking, which is provided, like ordinary bathing-stockings, with a sole of proper material.

15 In the drawing the leg portion A of the stocking is in one piece with the foot portion B. The appearance of a low shoe over the foot portion of the stocking is produced by

the heel portion C, which covers the heel of the stocking, and the tip D, which covers the toe portion of the stocking. The heel portion C has a flap with a buttonhole which buttons over the top of the foot portion B of the stocking.

The effect of my design may be heightened by having the portion A of a different color than the portions B, C, and D.

What I claim is—

The design for bathing-stockings substantially as shown and described.

This specification signed and witnessed this 16th day of December, 1896.

EDWIN A. GUINZBURG.
